COUPLING STABILIZER FOR MOINEAU PUMPS

John B. Wade, Arcadia, Calif., assignor to Food Machinery and Chemical Corporation, a corporation of Delaware

Application September 25, 1945, Serial No. 618,459

7 Claims. (Cl. 103—117)

1

This invention relates to improvements in Moineau pumps and a particular object of the invention is to reduce the vibration incident to the operation of this type of pump at high speeds.

The principle of the so-called Moineau pump is disclosed in U. S. Letters Patent to Rene Moineau, No. 1,892,217 and No. 2,028,407. This pump comprises a helical rotor rotatably disposed in a helically formed opening in a stator. The helical surfaces of the rotor and stator are so related as to form pockets between the rotor and stator which travel in a given direction as the rotor turns in the stator, thereby effecting a pumping action. When the rotor is thus turned, its axis describes a gyratory path about the central axis of the stator and in the reverse direction to that in which the rotor is rotated. This makes it necessary to transmit power to the rotor through a flexible element.

The coupling at present in general use for driving the rotor of this type pump is that disclosed in U. S. Letters Patent to James M. Hait, No. 2,346,426 issued April 11, 1944. The Hait coupling comprises a heavy steel cable, opposite ends of which are rigidly united with steel heads, the cable and portions of the heads being covered with a jacket of soft vulcanized rubber bonded to the metal parts. Use of the Hait coupling reduced the vibration experienced in rotating Moineau pump rotors at high speeds as is customarily done in wells. Another means of reducing this vibration by greatly lightening the rotor is comprised in a hollow Moineau pump rotor formed of expanded sheet metal which is disclosed in my copending application for U. S. Letters patent, No. 553,626 filed September 11, 1944.

It is an object of the present invention to provide a novel means of exercising further control over the vibration of a Moineau pump rotor.

The manner of accomplishing the foregoing objects, as well as further objects and advantages, will be made manifest in the following description taken in connection with the accompanying drawings in which:

Fig. 1 is a diagrammatic longitudinal sectional view of a section of a well showing installed therein a Moineau pump with which a preferred embodiment of the present invention is incorporated.

Fig. 2 is an enlarged longitudinal cross sectional view taken on the line 2—2 of Fig. 1 and illustrating the invention in greater detail.

Fig. 3 is an enlarged sectional view taken on the line 3—3 of Fig. 1 and illustrating the hollow

type of Moineau pump rotor with which my invention is preferably associated.

Fig. 4 is an enlarged cross sectional view taken on the line 4—4 of Fig. 2.

Referring specifically to the drawings, my invention is there illustrated as embodied with a well pump 10 of the Moineau type in a well casing 11. The pump 10 is suspended on the lower end of a pump tubing 12 having lower sections 13, 14, and 15 connected by collars 16 and 17. A pump tubing 12 forms a housing for and base upon which the working parts of the pump 10 are mounted and supported. These include a spider 20 which is gripped between adjacent ends of the tubing sections 13 and 14 and which supports centrally a lower drive shaft bearing 21 which, as shown in Fig. 1, is of the rubber water-lubricated type. Extending downwardly through the tubing 12 is a line shaft 22; the lower end of which journals in the bearing 21.

Clamped between adjacent ends of the tubing sections 14 and 15 is a spider 25 which supports co-axially with the tubing 12 a coupling stabilizer ring 26. This ring has a polished central upwardly tapered opening 27.

Screwed onto the lower end of the pump tubing 12 is the stator 30 of the pump 10, this having a soft rubber core 31 in which is molded a helical opening 32 which is double pitched and is adapted to receive a single pitched helical rotor 35. The rotor 35 is so shaped with respect to the configuration of the stator opening 32 that when the rotor is rotated in said opening, a series of pockets are formed between the rotor and the stator which travel in an axial direction, thereby effecting a pumping action. When the rotor 35 is so rotated in the stator 30, the axis of the rotor describes a gyratory path about the central axis of the stator travelling in the direction opposite to that in which said rotor rotates.

Power is transmitted between said shaft 22 and said rotor 35 by a flexible drive coupling 40 which is preferably of the type disclosed in the patent of James M. Hait above mentioned. This coupling includes steel heads 41 and 42 which are secured respectively to the lower end of the shaft 22 and the upper end of the rotor 35; a heavy steel cable 43, opposite ends of which are rigidly fixed in sockets 44 formed in said heads, and a jacket 45 of soft rubber which surrounds the cable 43 and portions of the heads 41 and 42 and is vulcanized thereto.

The pump 10 is adapted to draw water surrounding the stator 30 in the casing 11 inwardly through a screen 50 mounted on the lower end

of the stator 30 and force this water upwardly through the tubing 12 to the surface of the ground. This is accomplished by rotating the rotor 35 through the shaft 22. Efficiency requires that this rotation be at a fairly high rate and is ordinarily about 1500 R. P. M.

Owing to the gyration of the rotor 35 in the opposite direction to that in which it rotates in the stator 30, the flexible drive coupling 40 has a tendency to whip outwardly from the axis of the drive shaft 22. When the tube 12 is filled with water, the weight thus imposed upon the rotor 35 tends to straighten out the coupling 40 and diminish whipping of the latter.

I have found that whipping of the flexible coupling 40 may be reduced to an absolute minimum by confining this coupling within a ring such as the stabilizer ring 26 at a point intermediate opposite ends of the flexible portion of the coupling 40. The opening 27 in the stabilizer ring 26 is concentric with the axis of the shaft 22 and is so shaped as to be contacted by a mid portion of the coupling 40 when the coupling is flexed to adapt itself to the off set axes of its opposite ends when the pump is not running. The portion of the coupling located within the ring 26 is thus slightly eccentric relative to the ring as shown in Figs. 2 and 4.

The effect of the stabilizer ring 26 therefore when the pump 10 is running is to maintain the flexible coupling 40 in the normal flexed condition which it assumes when the pump is not running to adapt itself to the off set axes of the shaft 22 and the rotor 35. The stabilizer ring 26 thus prevents whipping of the flexible coupling 40 which would otherwise result from the fact that rotation of the pump rotor 35 causes its axis to describe a gyroscopic path about the axis of the stator 31 in the reverse direction to that in which the rotor is rotated.

I claim:

1. In combination: a housing; a stator connected to said housing and having a helical opening; a rotor rotatably disposed in said stator opening and so shaped relative thereto as to gyrate in the opposite direction to that in which it is turned in said stator opening; a shaft journalled in said housing for rotation in alignment with the axis of said stator; a flexible drive coupling, one end of which is connected to said shaft and the other end of which is connected to said rotor; and stabilizing means mounted in said housing and positioned to be engaged by said coupling as the latter rotates in transmitting power between said shaft and said rotor, to confine said coupling against the latter yielding to the action of unbalanced centrifugal forces operating thereon.

2. In combination: a housing; a stator connected to said housing and having a helical opening; a rotor rotatably disposed in said stator opening and so shaped relative thereto as to gyrate in the opposite direction to that in which it is turned in said stator opening; a shaft journalled in said housing for rotation in alignment with the axis of said stator; a flexible drive coupling, one end of which is connected to said shaft and the other end of which is connected to said rotor; and a stabilizing ring mounted in said housing to surround said coupling to confine the latter against whipping caused by centrifugal forces set up by said gyration of said rotor.

3. In combination: a housing; a stator connected to said housing and having a helical opening; a rotor disposed in said stator opening and so shaped relative thereto as to gyrate in the

opposite direction to that in which it is turned in said stator opening; a shaft journalled in said housing for rotation in alignment with the axis of said stator; a flexible drive coupling, one end of which is connected to said shaft and the other end of which is connected to said rotor; and a stabilizing ring mounted in said housing to surround said coupling to confine the latter against whipping caused by centrifugal forces set up by said gyration of said rotor, said ring being so mounted approximately midway between opposite ends of said coupling.

4. In combination: a housing; a stator connected to said housing and having a helical opening; a rotor rotatably disposed in said stator opening and so shaped relative thereto as to gyrate in the opposite direction to that in which it is turned in said stator opening; a shaft journalled in said housing for rotation in alignment with the axis of said stator; a sinuous flexible drive coupling, one end of which is connected to said shaft and the other end of which is connected to said rotor; and a stabilizing ring mounted in said housing to surround said coupling to confine the latter against whipping caused by centrifugal forces set up by said gyration of said rotor, said ring being so mounted approximately midway between opposite ends of said coupling, the axis of the opening in said ring being co-axial with said shaft.

5. In combination: a housing; a stator connected to said housing and having a helical opening; a rotor rotatably disposed in said stator opening and so shaped relative thereto as to gyrate in the opposite direction to that in which it is turned in said stator opening; a shaft journalled in said housing for rotation in alignment with the axis of said stator; a flexible drive coupling, one end of which is connected to said shaft and the other end of which is connected to said rotor; and a stabilizing ring mounted in said housing to surround said coupling to confine the latter against whipping caused by centrifugal forces set up by said gyration of said rotor, said ring being so mounted approximately midway between opposite ends of said coupling, the axis of the opening in said ring being co-axial with said shaft and tapering toward said drive shaft.

6. In combination: a pump tubing; a stator connecting with said pump tubing and having a helical opening; a rotor disposed in said stator opening and so shaped relative thereto as to gyrate in the opposite direction to that in which it is turned in said stator opening; a bearing in said pump tubing; a shaft journalled in said bearing for rotation in alignment with the axis of said stator; a flexible drive coupling, one end of which is connected to said shaft and the other end of which is connected to said rotor; and a spider mounted in said tubing, said spider having a central ring which surrounds said coupling at a point intermediate the ends of the flexible portion of said coupling so as to confine the part of said coupling surrounded by said ring substantially in the normal flexed condition which it assumes when said pump is not running.

7. In combination: a housing; a stator connected to said housing and having a helical opening; a rotor disposed in said stator opening and so shaped relative thereto as to gyrate in the opposite direction to that in which it is turned in said stator opening; a shaft journalled in said housing for rotation in alignment with the axis of said stator; a flexible drive coupling comprising heads connected to said shaft and to said

rotor, a wire cable, opposite ends of which are fixed to said heads, and a jacket of rubber bonded to and covering said cable; and stabilizing means mounted in said housing and positioned to be engaged by said coupling as the latter rotates in transmitting power between said shaft and said rotor, to confine an intermediate portion of said coupling against the latter yielding to the action of unbalanced centrifugal forces operating thereon.
